UNITED STATES PATENT OFFICE.

OSCAR S. McCURDY, OF WILKINSBURG, PENNSYLVANIA.

HEATING APPARATUS.

SPECIFICATION forming part of Letters Patent No. 769,318, dated September 6, 1904.

Application filed March 26, 1903. Serial No. 149,490. (No model.)

To all whom it may concern:

Be it known that I, OSCAR S. McCURDY, a citizen of the United States, residing at Wilkinsburg, in the county of Allegheny and State 5 of Pennsylvania, have invented certain new and useful Improvements in Heating Apparatus, of which the following is a specification, reference being had therein to the accompanying drawings, forming part of this specification, in which—

Figure 1 is a sectional view of a building equipped with my improved automatic heating generators and regulators. Fig. 1^a is a sectional detail view showing the supply-duct surrounding the hot-air pipe. Fig. 2 is a vertical sectional view, on an enlarged scale, through one of the heaters. Fig. 3 is a sectional detail view through the burner-valve on the line III III of Fig. 2, showing the valve 15 partly turned to admit gas. Figs. 4 and 5 are detail views showing the connections between the registers and the gas-valves in closed and open positions, respectively. Fig. 6 is a cross-sectional view through the burner-chamber on the line VI VI of Fig. 2. Fig. 7 is a cross-section above the heating-diaphragm on the line VII VII of Fig. 2.

My invention relates to heating apparatus for houses, &c.; and it has for its object to provide a heating device for air which will quickly heat a large volume as it circulates through the apparatus and also a burner and controlling-valve which can be accurately controlled and regulated. Similar subject-matter is 35 shown, described, and claimed in my companion application for heating apparatus, filed June 29, 1903, bearing the Serial No. 163,559.

Referring now to the drawings, 2 is a casing of sheet-iron or other material of any suitable 40 inclosing form or shape provided with a cold-air inlet-pipe 3, leading to its lower portion from any source, as the outside air. The pipe may, however, be omitted and one or more air-openings left in the casing, as will be readily understood. In the lower interior portion 45 of the casing is a burner consisting of a plurality of assembled headers 4, having numerous gas-outlet openings or jets 5, each header being supplied with a gas-pipe 6, connected 50 with a valve-casing 7, while a pilot-light jet 8

is also connected with the valve-casing and adapted to always receive a supply of gas at any position of the valve when the main supply is not cut off.

9 is the valve, rotatably mounted in the casing and having a tapering sealing portion 10 and an open cut-out portion 11. The width of the tapering sealing portion is slightly less than the width of the opening to the pilot-light pipe 8 or may be omitted entirely, while 55 it is sufficiently wide to cover the next adjacent burner-pipe and gradually wider for each next successive pipe or opening. By this construction when the valve is closed, as shown in Fig. 2, all of the burner-pipes will be shut 60 off, and upon turning it to one side or another gas will be supplied to one or more of the burners, as desired. The valve is preferably 65 tapered in form, having circular solid bearings at each end to insure a tight fit, and is 70 provided with a stem 12, having a lever 13 at the end. A spring 14 surrounds the stem, bearing against the valve-case and a washer 15, by which the valve is held tightly to its seat. The valve-case 7 is provided with a gas- 75 supply pipe 16, which may have a controlling or shut-off valve or cock.

17 is a hood surrounding the burner, having interior baffle-walls or obstructions 18, adapted to deflect the course of the burning 80 gas and to absorb heat therefrom and to radiate it from the exterior of the hood. Air is supplied to the burner through mixers 19 and openings in the base of the hood, through 85 which it may pass upwardly, as indicated.

Above the burner-chamber and extending across the interior area of the case 2 is the combined flue and radiating-diaphragm heater into which the products of combustion are discharged from the burner and through the openings in which the partially-heated air passes to become highly heated. This portion of the device is preferably in the form of a circular diaphragm of cast-iron, having a central downwardly-extending flue-opening 20 and 90 entrance-nozzle adapted to interfit and communicate with the interior of the burner-chamber. The flue-opening 20 is extended on a horizontal plane in a volute path, a similarly-arranged conduit being provided therefor 95 100

composed of inclosing walls 21. These are best shown in cross-section in Fig. 2, wherein the conduit-walls taper downwardly toward a point 22, widening out at or about their middle portion, being closely adjacent to each other and then tapering inwardly toward the top, which is preferably on a common level. The space between the sections of the conduits is joined by a web 23, strengthening-
10 ribs 24 being also located at intervals, while through the webs 23 are air-openings 25. Slanting openings 26, with surrounding integral walls, are cored through the casting at frequent intervals in opposite directions, 15 through which openings the air also passes upwardly from below. By this construction a very comparatively large area of interior surface is provided for circulation of gases of combustion, and their progress is considerably baffled and interfered with. The conduit finally terminates in an outlet-opening 27, from which waste gases are taken off to any suitable point of discharge, as a flue 28, Fig. 1. As the air passes upwardly around 25 the burner-hood and the lower surfaces of the radiator and through openings 25 and 26 it will become highly heated, absorbing the radiated heat, and will pass therefrom directly to the register 29. The heater may be connected directly with the register underneath, as shown in Fig. 2 and at the right of Fig. 1, or a pipe 30 may lead upwardly to the second or third floor, as shown at the left of said view.

35 The registers with which the hot-air conductor is connected may be of any well-known or usual kind wherein opening and closing gates 31 are provided, usually swinging on pivot-bearings 32 and so connected that all 40 the gates of a single register are opened and closed by foot or hand movement. The rocking or moving element of the register is provided with a single or double lever 33, between which and lever 13 of the valve-stem 45 12 are connecting rods or chains 34 or other suitable means by which motion will be imparted to the valve from the movement of the radiator. When the radiator is closed, the gas is entirely cut off except to the pilot 8, and when the register is open the full flow of 50 gas is thrown on, while at intermediate positions but one or more burners are supplied, and the supply to each burner is also correspondingly regulated. Thus it will be seen 55 that the desired amount of heat can readily be secured by opening or closing the register as much or little as required.

60 The apparatus is very economical of fuel, and as a separate heater is furnished for each room the temperature may be readily controlled therein independent of other rooms.

65 The entire device is very small and compact, simple, and cheap in construction, not liable to get out of order, and will commend itself to users of heat-generating apparatus.

It will be understood that other designs of burner-hood, radiating-diaphragm, casing, &c., may be employed and that various changes and modifications may be made by the skilled mechanic; but all such are to be 70 considered as within the scope of the following claims.

What I claim is—

1. A hot-air heater consisting of a casing provided with an air-supply opening, a burner, 75 a surrounding hood for the burner, and a radiating-diaphragm having a continuous interior flue communicating with the burner-hood and provided with an outlet-opening, said flue having tapering walls and provided with 80 air-circulating ports, substantially as set forth.

2. In a hot-air heater, the combination with a burner-chamber and a surrounding casing; of a transversely-arranged radiating-diaphragm extending across the area within the casing, having a continuous volute interior flue communicating with the burner-chamber and terminating in an outlet-opening, with transverse air-ports extending at intervals across 90 the flue, substantially as set forth.

3. In a hot-air heater, the combination with a burner-chamber and a surrounding casing; of a transversely-arranged radiating-diaphragm extending across the area within the 95 casing having a continuous volute interior flue communicating with the burner-chamber and terminating in an outlet-opening, with transverse air-ports extending at intervals across the flue, and a fuel-inlet valve adapted to control the supply of fuel to the burner-chamber, 100 substantially as set forth.

4. In a hot-air heater, the combination with a burner-chamber and a surrounding casing; of a transversely-arranged radiating-diaphragm extending across the area within the casing having a continuous volute interior flue communicating with the burner-chamber and terminating in an outlet-opening, with transverse air-ports extending at intervals across 110 the flue, and a fuel-inlet valve adapted to control the supply of fuel to the burner-chamber, with means for actuating the valve, substantially as set forth.

5. In a hot-air heater, the combination with 115 a burner-chamber and a surrounding casing; of a transversely-arranged radiating-diaphragm extending across the area within the casing having a continuous volute interior flue communicating with the burner-chamber and terminating in an outlet-opening, with transverse air-ports extending at intervals across 120 the flue, and a series of air-openings extending transversely between the adjacent volute channels, substantially as set forth.

6. In a hot-air heater, the combination with a burner-chamber and a surrounding casing; of a transversely-arranged radiating-diaphragm extending across the area within the casing having a continuous volute interior flue 130

- communicating with the burner-chamber and terminating in an outlet-opening, with transverse air-ports extending at intervals across the flue formed by diagonally-arranged in-
- 5 closing and separating walls integral with the main flue-structure, substantially as set forth.
7. In a hot-air heater the combination with a burner-chamber and a surrounding casing; of a transversely-arranged diaphragm extending across the area within the casing provided with a continuous interior flue communicating with the burner-chamber and terminating in an outlet-opening, said flue having tapering walls, with air-passages between the adjacent walls, substantially as set forth.
- 10 15 20 25 30 35 40 45
8. In a hot-air heater, the combination with a burner-chamber and a surrounding casing; of a transversely-arranged diaphragm extending across the area within the casing provided with a continuous interior flue communicating with the burner-chamber and terminating in an outlet-opening, said flue having tapering walls, with air-passages arranged at intervals through the flue, substantially as set forth.
9. In a hot-air heater, the combination with a burner-chamber and a surrounding casing; of a transversely-arranged diaphragm extending across the area within the casing provided with a continuous interior flue communicating with the burner-chamber and terminating in

an outlet-opening, said flue having tapering walls, with air-passages between the adjacent walls, and through the flue, substantially as set forth.

10. A diaphragm-flue consisting of a single 35 cast-metal body having a continuous interior volute flue with a central inlet-opening and a peripheral outlet-opening, with circulating transverse air-passages, substantially as set forth.

11. A diaphragm-flue consisting of a single 40 cast-metal body having a continuous interior volute flue with a central inlet-opening and a peripheral outlet-opening, said flue having tapering walls, with intervening perforating air-ports, substantially as set forth.

12. A diaphragm-flue consisting of a single 45 cast-metal body having a continuous interior volute flue with a central inlet-opening and a peripheral outlet-opening, said flue having tapering walls with diagonally-arranged transverse air-passages arranged at intervals across the flue, substantially as set forth.

In testimony whereof I affix my signature in presence of two witnesses.

OSCAR S. McCURDY.
